CLAIM

The ornamental design for a zipper pull, as shown and described.

DESCRIPTION

FIG. 1 is a front elevation view of a zipper pull showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a right perspective view thereof; and,

FIG. 8 is a using status perspective view for reference.

The broken lines are included for the purpose of illustrating portions of the zipper pull that form no part of the claimed design.
